UNITED STATES PATENT OFFICE.

FRANK B. PEEBLES, OF SYRACUSE, NEW YORK, ASSIGNOR TO THE LAMSON COMPANY, OF SYRACUSE, NEW YORK, A CORPORATION OF MASSACHUSETTS.

STOP DEVICE FOR CONVEYER SYSTEMS.

Application filed April 19, 1923. Serial No. 633,133.

To all whom it may concern:

Be it known that I, FRANK B. PEEBLES, a citizen of the United States of America, and resident of Syracuse, in the county of Onondaga and State of New York, have invented new and useful Improvements in Stop Devices for Conveyer Systems, of which the following is a specification.

This invention concerns conveyer systems 10 of that type in which article supporting carriers move along elevated tracks or rails, and relates more particularly to means for preventing interference of carriers approaching along converging tracks.

15 Conveyer systems of the type designated are commonly employed in packing establishments, warehouses, docks and the like and often comprise what may conveniently be termed "main" tracks with which branch 20 or feeder tracks converge at intervals. In some cases the main track is furnished with driving means, as for example an endless chain, for propelling the carriers along it, while the branch or feeder tracks may be of 25 gravity type, depending upon the inclination of their rails to cause the carriers to move toward the main track.

In a system such as just suggested, great care must be exercised to prevent collision 30 of carriers approaching the junction point along the main and branch tracks, respectively, as such collision not only tends to block the system and damage the individual carriers with their loads, but frequently 35 causes the articles being transported to fall and injure workmen passing beneath.

The principal object of the present invention is accordingly to provide a stop device 40 for use at the intersection of the tracks of such a system, operative automatically to prevent interference of carriers approaching the junction point.

In the accompanying drawings a preferred embodiment of the invention is illustrated and in such drawings:—

Fig. 1 is a fragmentary plan view of a conveyer system having the present invention embodied therein;

50 Fig. 2 is an end elevation of the devices shown in Fig. 1 looking in the direction of the arrow A in said figure; and

Fig. 3 is a side elevation of the parts shown in Fig. 1 looking in the direction of the arrow B in the latter figure.

55 Referring to the drawings, the numeral 1

indicates what may be termed the main track of a conveyer system of usual type, and 2 indicates a branch track converging toward the main track. As here shown the branch track lies in a plane above that of the main track and as it approaches the latter is inclined downwardly at 3. At the junction between the tracks a switch point 4 is provided, pivoted at 5 to swing toward and from the main track and normally held 60 in contact with the latter by means of a spring 5a.

Above the main track, and substantially parallel therewith, a pair of supporting rails 6, 7 are provided upon which carriages 8 70 travel. These carriages support a driving chain 9 furnished at intervals with projecting lugs 10 for engagement with article supporting carriers resting upon the main track.

As herein disclosed a pair of substantially parallel endless chains 12, 13 are associated with the branch track 2, such chains being trained over guiding sprockets 14, 15 and being connected at intervals by bars 16. 80 These bars constitute driving elements for moving carriers such as 11a along the branch tracks 2 until the carriers reach the inclined portions 3 of the latter, whereupon they descend by gravity toward the main track. 85 All of the above features are of known construction and form no essential part of the present invention.

At a point near the junction of the branch track with the main track, a support 17 is 90 provided which has bearings for a vertical shaft 18. A bell crank lever comprising the arms 19, 20 is secured to the lower end of the shaft 18. Normally the shaft is held in the position shown in the drawings by means of a coil spring 21 encircling it. In this position of the parts, the arm 19 of the bell crank lever extends transversely across the path of movement of the carriers moving along the main track 1.

A pair of brackets 22, 23 are mounted upon the support 17 and provide bearings for a horizontal shaft 24. A stop element, here shown as a substantially flat plate 25, is secured to the shaft 24 and normally depends 105 across the inclined portion 3 of the branch track so as to lie in the path of carriers moving down the latter. A controlling arm 26 is also secured to the shaft 24, and preferably lies substantially parallel to the stop 110

element 25. The lower end of the controlling arm projects across the plane of movement of the arm 20 of the bell crank lever.

The operation of the device is substantially as follows: If a carrier such as 11^a is allowed to descend the inclined track 3, and provided a carrier is not at the same time passing along the main track, the descending carrier engages the stop element 25, and, as the latter is free to swing, merely pushes it out of the way and continues its descent, passing onto the main track, along which it may be propelled by one of the lugs 10 of the chain 9. If, however, at the instant a carrier starts to descend the incline 3, a carrier should be moving along the main track, the engagement of the latter carrier with the arm 19 will swing the bell crank lever until its arm 20 comes into engagement with the controlling arm 26. So long as the carrier on the main track remains in engagement with the arm 19 the controlling arm and the stop member are restrained from movement so that a carrier descending the inclined rail 3 will be stopped when it comes into contact with the member 25. The arm 19 is preferably made long enough to remain in engagement with a carrier passing on the main track until the latter has passed the danger zone. Immediately upon release of the arm 19 by the passing carrier, the spring 21 restores the shaft 18 with its bell crank to normal position, thus releasing the stop member 25 and permitting the carrier upon the branch track to continue its descent.

By this arrangement any possible interference or collision of carriers approaching the junction point of the two tracks is avoided, thus making it unnecessary to keep a workman at the junction point to hold back the carriers upon the branch track and prevent their collision with carriers on the main track.

While certain forms of driving mechanism have herein been illustrated as desirable for moving the carriers along their tracks, it is clear that the present invention is not in any manner restricted to use with such devices, but is applicable in general to systems in which converging tracks are used.

I claim:

1. A conveyer system comprising a pair of tracks converging to a junction point, a movable stop normally extending across one of said tracks and normally movable freely from across the track by a carrier moving therealong, and an actuator, operable by a carrier approaching the junction point along the other track, to prevent movement of the stop from normal position.

2. A conveyer system comprising a pair of tracks converging to a junction point, a pivotally supported stop normally depend-

ing over one of said tracks in the path of carriers moving along said track but normally free to be moved out of the way by a passing carrier, and an actuator operable by a carrier approaching the junction point along the other track to restrain the stop member against movement whereby to arrest a carrier moving along the first track.

3. A conveyer system comprising a pair of tracks converging to a junction point, a freely turning shaft extending across and above one of said tracks, a stop member secured to said shaft and normally depending into the path of carriers moving along said track, an arm secured to the shaft, and an actuator movable by a carrier approaching the junction point along the other track and having an element engageable with said arm for restraining the latter and thereby the stop member, from movement.

4. A conveyer system comprising a main track and a branch track converging to a junction point, a normally inoperative carrier stop associated with the branch track, and an actuator associated with the main track and operable by a carrier passing along the latter to render the stop operative, said actuator comprising an arm normally extending across the path of carriers moving along the main track, and an arm for controlling the stop.

5. A conveyer system comprising a pair of tracks converging to a junction point, a freely swinging stop normally positioned across one of said tracks, and a stop actuator associated with the other track, said actuator comprising a lever having one arm normally positioned to be moved by a carrier passing therealong, and a second arm constituted and arranged to restrain the stop from movement while a carrier engages the first named arm of the lever.

6. A conveyer system comprising a main track and a branch track converging to a junction point, a freely turning, substantially horizontal shaft extending across the branch track, a stop secured to the shaft and depending in the path of carriers moving along the branch track, a controlling arm secured to the shaft, a bell crank lever turning about a substantially vertical axis, one arm of the lever normally extending across the main track in position to be swung by carriers moving therealong, and a spring retaining the bell crank lever in normal position, the other arm of the lever being constructed and arranged to engage the aforesaid controlling arm whereby to prevent movement of the stop while a carrier is passing on the main track.

Signed by me at Syracuse, N. Y., this sixteenth day of April, 1923.

FRANK B. PEEBLES.
